UNITED STATES PATENT OFFICE.

SETH J. WAKELEY, OF NEW YORK, N. Y.

DIE OR NIPPLE HOLDER.

SPECIFICATION forming part of Letters Patent No. 314,087, dated March 17, 1885.

Application filed July 31, 1884. (No model.)

To all whom it may concern:

Be it known that I, SETH J. WAKELEY, a citizen of the United States, residing in the city and county of New York, in the State of New York, have invented a new and useful Improvement in Die or Nipple Holders for Machines for Threading Pipe and Nipples, of which the following is a specification, reference being had to the accompanying drawings.

10 This invention relates to the die or nipple holders which are employed in the sliding carriage which moves to and fro toward and from the rotary main spindle of a pipe-threading machine, and which are adapted to receive 15 threading-dies for cutting threads on pipes held in vise-jaws fitted to the said spindle, or to receive vise-jaws for holding nipples or pipe to be threaded by dies in the rotary main spindle.

20 The improvement consists in a novel construction of the holder, hereinafter described, whereby the jaws or dies are enabled to run very close up to the rotary main spindle, and whereby, when vise-jaws are employed in the 25 holder, they may be made to securely hold a short piece of pipe by a very short hold, and whereby, also, very convenient provision is afforded for rapidly changing the dies for others of different size through the whole range of 30 variations of sizes ever used in such machines, and for as rapidly changing dies for vise-jaws, and vice versa.

Figure 1 in the drawings is a face view of a die or nipple holder constructed according to 35 my invention, and containing a pair of threading-dies. Fig. 2 is a longitudinal central section of the same. Fig. 3 is a transverse section of the same. Fig. 4 is a face view of the slides containing a pair of vise-jaws.

40 Similar letters of reference indicate corresponding parts in the several figures.

A is the main plate of the holder, which is of ordinary construction, and firmly secured in the usual way to the sliding carriage of the 45 pipe-threading machine, with its opening *a* concentric with the axis of the rotary main spindle of the machine. This plate is constructed with parallel grooved guides *a'*, between and within which the open slide B is fitted to slide 50 freely, and is also provided with a projecting head, *b*, which is bored for the reception of the plainly-turned neck of the hollow screw C,

which is free to turn therein, but prevented from moving lengthwise therein by nuts or collars *c c'*, which are provided on the said screw 55 and so secured thereon as to be prevented from turning. The exterior thread of this screw works in a female screw-thread or nut provided at *n* in one end of the slide B.

In the opposite end of the slide B to that in 60 which the screw C works there is a mortise or mortise-like opening, *d d*, for the entrance into said slide of the screw-threading dies D D' or the vise-jaws E E', and the sides of the said slide are made with internal grooves, *e e*, which 65 conform to the ends of the said mortise *d d*, and to which the dies D D' are fitted. One die, D', or one vise-jaw, E', is secured by pins *f f* to the grooved slide F', which forms the head of the male screw F, which is fitted to a 70 female screw-thread in the hollow screw C, the said pins *f f* passing through holes in the said slide F' and the said die or jaw, so that the said die or jaw is compelled to move with the screw. The slide F' is fitted and guided between the straight parallel sides of the opening in the slide B. The other die, D, or jaw 75 E, is confined within the slide by a block, G, which fits the mortise *d* in the end of the slide B, and is secured therein by pins *h h*, inserted 80 through the said die or jaw and slide.

The grooves *e e* in the slide B are represented as fitted with packing-pieces *i i*, which are set up by set-screws *j j*, for the purpose of keeping the dies sufficiently tight in their 85 places for accuracy of work, while leaving them free to move as required.

The dies and holding-jaws are so formed and fitted to the slides that the center of their opening is opposite the center of the hole *a* in the main plate and in line with the axis of the rotating main spindle of the machine, and this position is always maintained in the opening and closing adjustment of the dies or jaws by the action of the two screws C and F, which are 90 of corresponding pitch, but of opposite inclinations, one being right-handed and the other left-handed. The adjustment is effected by a wrench or handle applied to the head of the screw C, which causes the slide B to be 100 moved in either direction, and the slide F to be moved in the other direction, according to the direction in which the screw C is turned.

To change the dies for others of different

size, or to change dies for jaws, or vice versa, it is only necessary to take out the pins *h h*, and take out the block *G* from the mortise *d d*, when the dies or jaws may both be withdrawn 5 through the said mortise. The substitute dies or jaws are inserted through the mortise, and secured by replacing the block *G* and the pins *h h*.

This die and vise holder provides for the 10 quick opening and closing adjustment of the dies and vise-jaws, and also for easily and quickly changing the dies and jaws, the method of providing for the removal and insertion of the dies and jaws through the mortise in the end of the slide *B* obviating the necessity of removable face-plates, which add to the thickness of the slide, enables the dies or jaws to come closer up to the rotary main 15 spindle, which is of especial advantage in threading nipples or very short pieces of pipe.

In the use of this die and holder it is not necessary to reverse the machine after cutting the thread.

What I claim as my invention, and desire 25 to secure by Letters Patent, is—

1. The combination, in a die or work holder for the sliding carriage of a pipe-threading machine, of the two slides fitted one within the other, the outer one having an opening in one end for the introduction of the dies or 30 jaws of both slides, and a block and means of securing the same in said opening for retaining the dies, substantially as herein described.

2. The combination of the plate *A* of the carriage of a pipe-threading machine, the slide *B*, fitted to said plate, the slide *F'*, fitted to said slide *B*, the screws *C F*, for moving the said slides in opposite directions, and the dies or vise-jaws within and between said slides, the said slide *B* having a mortise, *d d*, in one end 35 for the introduction of the dies or jaws, and a groove, *e*, conforming to said mortise, for guiding and retaining the dies or jaws, substantially as herein described.

SETH J. WAKELEY.
